2,545,471

SHOE SOLE CONDITIONING MACHINE.

John H. Kelly and Harry H. Teal, Pittsburgh, Pa.;
said Teal assignor to said Kelly

Application July 20, 1948, Serial No. 39,654

12 Claims. (Cl. 69—1)

1

This invention relates generally to the art of conditioning the surfaces of shoe soles made of leather or resinous soling material preparatory to the application of an adhesive for attaching the same to foot gear and more particularly to the apparatus for automatically conditioning shoe-sole surfaces. This invention may advantageously be employed in the steps of shoe manufacture as well as shoe and boot repairing and with slight modifications may be employed for use in kindred arts wherein the surfaces of the material must be prepared with a treated nap and all of the original surface eradicated for receiving a cementitious substance for attaching the same to another member that might have a similarly prepared surface.

In conditioning the surface of leather and resinous soling material preparatory to attaching it to a boot or shoe it is desirable to have a uniform nap on the surface of the material and to completely eradicate the original surface in the zone of the conditioning band that surrounds the perimeter of the sole. Many methods and apparatus have been tried to obtain such a surface and the only method that has been proven successful for preparing leather soles is by the use of the cutter as disclosed in U. S. Letters Patent 2,429,822, issued October 28, 1947, in a machine such as disclosed in Letters Patent 2,287,999, issued June 30, 1942. However, it is necessary to manually control the movement of the leather through the machine disclosed in the later patent and it is not suited for producing a uniform nap on a sole of resinous material.

The principal object of this invention is the provision of method and apparatus for automatically conditioning a leather and resinous shoe sole surface.

Another object is the provision of apparatus for controlling the width and extent of a uniform conditioning surface band around the perimeter of a shoe sole.

Another object is the provision of apparatus determining the iron or thickness of a conditioned surface around the perimeter of a shoe sole.

Another object is the provision of apparatus for opening and closing the throat in an automatic shoe sole surface conditioning machine.

Another object is the provision of a hard metal guide surface made of a material such as tungsten carbide and so disposed as to offer a resistance to control, with a resilient pressure roll, the automatic movement of the shoe sole through a surface conditioning machine.

2

Other objects and advantages appear herein-after in the following description and claims.

The accompanying drawings show, for the purpose of exemplification, without limiting the invention or the claims thereto, certain practical embodiments of the invention wherein:

Fig. 1 is a plan view of the automatic shoe sole conditioning machine comprising this invention;

Fig. 2 is a side elevation of the machine shown in Fig. 1 with the cover removed for the purpose of showing the cutter and the pressure roll;

Fig. 3 is a vertical section of the machine as shown on the line 3—3 of Fig. 1;

Fig. 4 is a detailed view of parts shown in Fig. 3 and with parts of the machine being broken away to illustrate the gap opening mechanism;

Fig. 5 is a perspective view of the conically shaped pressure roll that may be employed on this machine in place of the cylindrical roll illustrated in Figs. 1 to 3, inclusive;

Fig. 6 is a perspective view of the shoe sole guide block; and

Fig. 7 is a view similar to Fig. 6 showing a modified form of a shoe sole guide block.

Referring to the figures of the drawing, the shoe sole conditioning machine is mounted on the base 1 which may be assembled on a standard that contains a motor and a blower unit together with the conduit system for cooling the cutter mechanism and withdrawing the cuttings from the vicinity of the conditioning operation. The motor employed to drive the machine may be of the ordinary induction type or it may be variable in speed. The motor is arranged to drive the shaft 2 through a V-belt 3 engaging on the pulley 4 at the rear end of the shaft 2. The shaft 2 extends through and is journaled in the speed reducing mechanism 5 of any suitable design.

The forward end of the shaft 2 extends through an anti-friction bearing 6 and having its front end extending into the cutting chamber 7 of the table member 8. The end of the shaft 2 is arranged to receive the cutter 10 which is held thereon by the left hand screw 11 and the clamping washer 9 and the spacer 12. As viewed in Fig. 2 the cutter rotates in a clockwise direction and is preferably of the design disclosed in Patent 2,429,822 with the interrupting teeth following a left hand helix, the cutter being made from a single blank of any desirable width in accordance with the width of the surface to be conditioned on the shoe sole. The cutter is formed so that it may be turned end-for-end on the shaft 2 and is provided with duplicate cutting profiles to increase the life of the cutter.

40 The forward end of the shaft 2 extends through an anti-friction bearing 6 and having its front end extending into the cutting chamber 7 of the table member 8. The end of the shaft 2 is arranged to receive the cutter 10 which is held thereon by the left hand screw 11 and the clamping washer 9 and the spacer 12. As viewed in Fig. 2 the cutter rotates in a clockwise direction and is preferably of the design disclosed in Patent 2,429,822 with the interrupting teeth following a left hand helix, the cutter being made from a single blank of any desirable width in accordance with the width of the surface to be conditioned on the shoe sole. The cutter is formed so that it may be turned end-for-end on the shaft 2 and is provided with duplicate cutting profiles to increase the life of the cutter.

45 The forward end of the shaft 2 extends through an anti-friction bearing 6 and having its front end extending into the cutting chamber 7 of the table member 8. The end of the shaft 2 is arranged to receive the cutter 10 which is held thereon by the left hand screw 11 and the clamping washer 9 and the spacer 12. As viewed in Fig. 2 the cutter rotates in a clockwise direction and is preferably of the design disclosed in Patent 2,429,822 with the interrupting teeth following a left hand helix, the cutter being made from a single blank of any desirable width in accordance with the width of the surface to be conditioned on the shoe sole. The cutter is formed so that it may be turned end-for-end on the shaft 2 and is provided with duplicate cutting profiles to increase the life of the cutter.

50 The forward end of the shaft 2 extends through an anti-friction bearing 6 and having its front end extending into the cutting chamber 7 of the table member 8. The end of the shaft 2 is arranged to receive the cutter 10 which is held thereon by the left hand screw 11 and the clamping washer 9 and the spacer 12. As viewed in Fig. 2 the cutter rotates in a clockwise direction and is preferably of the design disclosed in Patent 2,429,822 with the interrupting teeth following a left hand helix, the cutter being made from a single blank of any desirable width in accordance with the width of the surface to be conditioned on the shoe sole. The cutter is formed so that it may be turned end-for-end on the shaft 2 and is provided with duplicate cutting profiles to increase the life of the cutter.

55 The forward end of the shaft 2 extends through an anti-friction bearing 6 and having its front end extending into the cutting chamber 7 of the table member 8. The end of the shaft 2 is arranged to receive the cutter 10 which is held thereon by the left hand screw 11 and the clamping washer 9 and the spacer 12. As viewed in Fig. 2 the cutter rotates in a clockwise direction and is preferably of the design disclosed in Patent 2,429,822 with the interrupting teeth following a left hand helix, the cutter being made from a single blank of any desirable width in accordance with the width of the surface to be conditioned on the shoe sole. The cutter is formed so that it may be turned end-for-end on the shaft 2 and is provided with duplicate cutting profiles to increase the life of the cutter.

This cutter is preferably made with tungsten carbide tips or other suitable hard metal to give it lasting qualities and relative long life in service.

It will be noted that the teeth of the cutter extend slightly above the surface 13 of the table 8 when the plate 14, that covers the face of the cutter chamber on the table casing, is removed. As shown in Fig. 2 a series of holes or openings 15 are found adjacent the curved edge of the cutter chamber and also around the shaft 2. The purpose of these holes is to permit the blower to exhaust air through the cylindrical throat 16 of the cutter chamber for the purpose of removing the cuttings from the vicinity for the cutting operation and also for drawing air in around the cutter itself to keep the cutter and the anti-frictional bearing cool during the operation of the machine as well as to remove the cuttings. It has been found that this method of cooling the bearing and the cutter materially increases the life of both members, particularly when they are required to function on a twenty-four hourly schedule in conditioning the surface of shoe sole material.

The table surface 13 is provided with slots 17 disposed in the same vertical plane as the axis of the shaft 2 for the purpose of receiving the key 18 on the underside of the guide plate 20 shown in Fig. 6. A portion of the undersurface of the guide plate 20 rests on the surface of the table 13 and is permitted to be adjusted fore and aft by means of the clamping pin wrench 21 which may be adjustably tightened and loosened. The threaded portion of the clamping pin wrench 21 passes through the slot 23 of the guide plate 20 and into a mating threaded opening in the table surface 13.

The guide plate 20 is provided with spaced arcuate surfaces 24 and 25 which are preferably tipped with a very hard material such as tungsten carbide. The guide surface 24 is shown to be a round pellet of carbide brazed or otherwise secured on the top of the key 18; whereas the arcuate guide surface 25 is brazed or otherwise secured to the edge of the guide plate 20 in spaced relation with the guide surface 24 providing a nest 26 between these arcuate guide surfaces. Above the guide surface 25 a lip 27 is constructed so that it may overhang the guide surface 25 to prevent light shoe soles from raising as they pass in contact with the guide surfaces 24 and 25. It will also be noted in Fig. 6 that a portion of the plate 20 is beveled as indicated at 28 above the guide surface 25 to provide clearance for the pressure roll 30. The construction lines 31 and 32 shown in Fig. 6 illustrate the relative position of the guide surfaces 24 and 25. The line 31 represents the horizontal line disposed at right angles to the axis of the shaft 2. The construction line 32 is in the same horizontal plane as the line 31 and is shown to be at an angle of twenty-five degrees from the line 31. This angle may be varied. It of course should not be ninety degrees but broad shoe soles may be automatically fed through the machine if the angle between the construction lines 31 and 32 is materially less than twenty-five degrees or in the order of eight to ten degrees. However, such an angle would be improper for use with a shoe sole having a very narrow toe such as used on ladies' shoes. The narrow toe would lock itself in the nest 26 and refuse to go through the machine if the angle is too great, or would be ejected forcefully from the machine before completion of the conditioning cycle if the angle

is too small. However, for leather and resinous shoe sole material the angle of twenty-five degrees is found to be preferable and functions satisfactorily for many different radii of curvature in the toe of shoe soles.

The speed reducer 5 is provided with the forwardly extending shaft 34 and is arranged to receive the gear 35 which is in mesh with the gear 36 mounted on the shaft 37 that lies above the shaft 2 and parallel therewith. A frame 38 is pivotally mounted on the shaft 34 and fastened thereto by the clamping washer and screw as indicated at 40. The frame 38 carries the bearings 41 for the shaft 37 and also the enclosed housing 42 that covers the gears 35 and 36. The other end of the frame 38 extends to the right as indicated at 43 and is provided with the socket 44 for receiving the upper end of the spring 45 that is held in compression between the frame end 43 and the spring tension adjusting mechanism 46 supported on the base.

The speed reducer 5 is arranged to provide a speed of approximately seventy to one between the shafts 2 and 37 whether the shaft 2 is operating at the speed of two thousand or five thousand R. P. M. or any selected speeds that is desired to be employed which may be obtained by the variable speed motor or the system of pulleys such as the pulley 4 in rotating the shaft 2.

The outer end of the shaft 37 is arranged to receive the pressure roll 30 and hold the same in place by means of the knurled nut 47 tightened on the threaded end of the shaft 37. As previously stated, the pressure roll shown in Figs. 1 to 3, inclusive, is cylindrical and is made of a resilient material such as a plastic or rubber and is frequently referred to as an elastomer material. It is preferable that this material be resilient and mounted on a steel core. It will be noted from Figs. 1 and 3 of the drawings that the inner edge of the pressure roll 30 lies just in front of the arcuate guide surface 24 and overlaps the same. As illustrated in Figs. 2 and 3 the pressure roll lies above the cutter 10 and is prevented from engaging therewith by means of the adjustable stop pin 48. When a shoe sole is inserted in the gap 50 between the pressure roll 30 and the cutter 10 its thickness or iron measurement will force the pressure roll upwardly rocking the frame 38 about the shaft 34 and causing the other end of the frame 43 to further compress the spring 45. However, the gap 50 may be limited in the degree of its opening by means of the micromatic iron selector stop as illustrated at 51 which comprises the post 52 set within the swiveling block 53 mounted to swivel on the base 1 by means of the pivot pin 54. The top of the post is of hardened steel and is arranged to engage the fine threaded screw member 55 that is provided with a notched head 56, the notches of which are engaged by the spring finger 57 attached to the housing 42. By rotating the screw 55, which may be calibrated directly in irons with reference to the spring finger 57, shown in Figs. 1 and 2, one may vary the gap 51 and thereby limit the degree of opening in the gap 50 between the pressure roll 30 and the cutter 10. This is particularly advantageous for use in reducing the forepart of a shoe sole at the same time the surface is being conditioned. It is also advantageous for use in selecting the proper iron of the shoe sole to determine the correct pressure applied through the pressure roll at the gap 50. As shown in Fig. 3 the swiveling block 53 is provided with a roller 58 on the

rearface thereof that engages the vertically disposed stationary backup bearing block 60. The vertically disposed rod 61 slides through an opening in the base 1 and is connected to a foot treadle that is spring biased to raise the rod to the position shown on the drawing. The rod 61 has the cam block 62 secured thereto and a forty-five degree angle cam surface 63 overlies the roller 58. When the foot treadle is depressed to draw the rod 61 downwardly the cam surface 63 engages the roller 58 causing the block 53 to swing on the pivot 54 moving the pin 52 from underneath the adjustable iron stop screw 55 and permitting the latter to lower so that the frame 38 may pivot on the shaft 34 and raise the pressure roll materially above the cutter 10. This action permits the operator to open the gap 50 between the pressure roll and the cutter for the purpose of inserting and removing the sole from the throat without improperly scoring the sole. The block 53 may be spring biased to swing back into position when the foot treadle is released to permit the rod 61 to raise. In order to expedite the pivoting of the frame 38 in a clockwise direction the rod 61 is permitted to extend up through the outer end 43 of the frame 38 and a stop nut 64 and a lock nut 65 are adjustably positioned on the rod for the purpose of engaging the upper surface of the frame, causing it to lower when the foot treadle is depressed. When the foot treadle is released and the block 53 swings back into the normal position as shown the post 54 is again in position to properly gauge the gap 51 for controlling the gap 50 between the pressure roll and the cutter. Although, as shown on the drawings, the distances between the gaps 50 and 51 to the axis of the shaft 34 are equal it is obvious that one may increase the distance from the gap 51 and the shaft 34 and thereby increase the effectiveness of this control of the micro thread on the adjusting screw 55.

In the manufacture of shoes it is frequently desirable to have a forepart reduction on the shoe soles, which reduction is in the nature of a beveled edge around the sole from the inner ball around the toe to the outer ball of the shoe, which reduction is ordinarily less than the shank reduction. It is an important object of this invention to provide a machine that will eliminate the step of the forepart reduction on a sole and at the same time provide a conditioned surface on the shank reduction. This is accomplished by first reducing the shank to the proper degree as an independent operation and then inserting the shank end of the sole into the gap 50, releasing the treadle to cause the pressure roll to engage the tread surface of the sole and permit the machine to automatically feed it therethrough. The machine will then condition the previously reduced shank and when the sole reaches the ball line, which has not been reduced, the cutter will not only produce the forepart reduction on the sole but also will condition the surface thereof. This reduction and conditioned surface continues around the toe of the sole to the other ball line and then continues along the shank to the end of the sole and merely conditions the previously reduced shank surface. Thus, this machine entirely eliminates the operation of forepart reduction in the preparation of shoe soles.

In order to perform the forepart reduction in a shoe sole it is necessary to provide a pressure roll having a conical shape such as the frusto conical roll disclosed in Fig. 5 wherein the roll

66 is of the same character as the pressure roll 30 but is conical in shape and is mounted on the sleeve 67. The inner end of the sleeve, as shown in Fig. 5, illustrates the manner in which the pressure rolls are keyed to the shaft 37. The shaft 37 is provided with a pin through its center, the ends of which are permitted to lie in the semi-cylindrical cross groove 68. Thus, when the pressure roll 66 is placed in the machine with the small end of the frusto conical surface toward the front of the machine, the cutter will produce a forepart reduction on the sole or a reduction completely around the sole if the shank portion has not been previously reduced and at the same time condition the surfaces. The reason for previously reducing the shank is that the reduction in the shank is ordinarily greater than the reduction of the forepart.

As shown in the drawings the surface of the pressure roll is substantially co-extensive to that of the cutter. However, it is preferable in some instances to mount the pressure roll on its shaft so that it extends outwardly at least one or more dimensions of the pitch of the cutter teeth. This permits the conditioned surface to be made to the edge of the sole. By adjusting the relative positions of the pressure roll and the cutter the conditioned surface may be spaced from the edge of the sole or by adjusting the guide block 20 the width of the conditioned surface may be changed. When a very wide conditioned surface or band is required a second cutter section may be added in place of the spacer 12 as shown in Fig. 3.

When the shank portion of a sole is inserted in the gap and the pressure roll is permitted to force it into engagement with the cutter the cutting action of the teeth forces the sole to the left owing to the fact that the teeth are of the left hand helix. A lateral thrust is given to the sole causing it to bear against the guide surfaces 24 and 25. The pressure roll acts as a hold back on the sole and permits the teeth of the cutter to properly condition the surface and raise a nap whether it be a leather sole or a resinous material. The edge of the sole engaging the guide block surfaces 24 and 25, together with the lateral thrust created by the cutter, causes these guide block surfaces to function in resisting the movement of the sole in engagement therewith. This resistance to movement, together with the hold back feature of the pressure roll and in conjunction with the proper spacing of the guide block surfaces 24 and 25, permits the sole to move rapidly through the gap around its entire perimeter without the aid of manual control, thereby automatically conditioning the attaching surface of the sole. Again it has been tried to allow the pressure roll to rotate freely on the shaft. However, if the pressure roll is not given the characteristic to hold back the sole it will travel so fast through the gap 50 that the surface is not properly conditioned. It is therefore obvious that resistance must be applied to three or more points of the sole for the purpose of automatically carrying it through the machine, first by the hold back pressure roll and second by the two resistant guide surfaces 24 and 25. This discovery has proven to be a very important object of this invention.

In the guide block 70, shown in Fig. 7, the resistant guide surface 25 has been replaced by the ball bearing 71 which is mounted in the semi-spherical socket 72 within the dimensions of the plate 70. The relative position of the sole edge engaging surface on the ball bearing 71 is the

same as that of the resistant guide surface 25. In other words, the construction line 32 is tangent to the resistant guide surface 24 and the surface of the ball bearing 71. The ball bearing 71 has been found to work more satisfactorily in a machine for conditioning a wide track on soles of resinous material. The important feature is to provide a movable guide surface at this point, which movable guide surface could be in the nature of a roller. However, the structure shown, is preferable. When producing a wide track conditioned surface around the perimeter of a shoe sole as previously stated it is necessary to employ two cutters in place of one, which condition doubles the lateral thrust on the shoe sole and it is therefore necessary to reduce some of the resistance offered by the guide block by replacing the surface 25 with a movable surface such as the ball bearing 71 shown in Fig. 7.

While, for clarity of explanation, certain preferred embodiments of this invention have been shown and described, it is to be understood that this invention is capable of many modifications, that changes in the construction and arrangement may be made therein and that certain parts may be employed without conjoint use of other parts and without departing from the spirit and scope of this invention.

We claim:

1. In a shoe sole conditioning machine, the combination of a table surface having an opening, a rotary cutter member capable of producing a lateral thrust in the direction of its rotation and mounted to have a portion of its cutting surface extending through said opening above the surface of said table, a rotary resilient pressure roll member mounted above said table with its axis parallel to the axis of the rotary cutter member and forming a gap therewith for receiving and discharging a shoe sole, means to maintain proportionate speed ratios of said members relative to each other and to maintain the rotation of said members in opposite directions to move the sole through said gap, shoe sole resistant guide means mounted on the table surface and having an outer arcuate sole edge engaging surface, an intermediate point on said sole edge engaging surfaces being disposed in the plane passing through the axis of said members and adjacent said gap, second shoe sole resistant guide means mounted on said table surface and having an outer arcuate sole engaging surface in the same horizontal plane as the first sole edge engaging surface and spaced from the discharge side of said gap, the plane tangent to the sole edge engaging arcuate surfaces of both of said guide means being disposed at an angle less than ninety degrees to the plane passing through the axes of said members.

2. In a shoe sole conditioning machine, the combination of a table surface having an opening, a rotary cutter member capable of producing a lateral thrust in the direction of its rotation and mounted to have a portion of its cutting surface extended through said opening above the surface of said table, a conical rotary resilient pressure roll member mounted above said table with its axis parallel to the axis of the rotary cutter member and having a gap therewith for receiving and discharging a shoe sole, means to maintain proportionate speed ratios of said members relative to each other and to maintain the rotation of said members in opposite directions to move the shoe sole through said gap, shoe sole resistant guide means mounted on the table surface and having an outer arcuate sole edge en-

gaging surface, an intermediate point on said guide means being disposed in the plane passing through the axes of said members and adjacent said gap, said shoe sole resistant guide means mounted on said table surface and having an outer arcuate sole engaging surface in the same horizontal plane as the first guide means and spaced from the discharge side of said gap, the plane tangent to the sole edge engaging arcuate surface of both of said guide means being disposed at an angle less than ninety degrees to the plane passing through the axes of said members.

3. The structure of claim 2 characterized in that the widths of the cutter and the pressure roll are substantially co-extensive to one another.

4. The structure of claim 3 characterized in that the sole edge engaging surface of the first guide means lies over a portion of the said cutter members.

5. The structure of claim 2 which also includes means to adjust the position of the sole edge engaging surfaces relative to the cutter and pressure roll members.

6. The structure of claim 2 characterized in that both of said shoe sole resistant guide means are fixed relative to each other.

7. The structure of claim 2 which also includes adjustable stop means for limiting said gap between the members.

8. In a shoe sole conditioning machine, the combination of a table surface having an opening, a rotary cutter member capable of producing a lateral thrust in the direction of its rotation and mounted to have a portion of its cutting surface extended through said opening above the surface of said table, a rotary resilient pressure roll member mounted above said table with its axis parallel to the axis of the rotary cutter member and having a gap therewith for receiving and discharging a shoe sole, means to maintain proportionate speed ratios of said members relative to each other and to maintain the rotation of said members in opposite directions to move the shoe sole through said gap, shoe sole resistant guide means mounted on the table surface and having a pair of spaced arcuate sole edge engaging surfaces forming a nest therebetween, an intermediate point on one of said sole edge engaging surfaces being disposed in the plane passing through the axes of said members and adjacent said gap, and the other sole edge engaging surface lying in the same horizontal plane and spaced from the discharge side of said gap, the plane tangent to the sole edge engaging arcuate surfaces of both of said guide means being disposed at an angle less than ninety degrees to the plane passing through the axes of said members.

9. In a shoe sole conditioning machine, the combination of a table surface having an opening, a rotary cutter member capable of producing a lateral thrust in the direction of its rotation and mounted to have a portion of its cutting surface extended through said opening above the surface of said table, a rotary resilient pressure roll member mounted above said table with its axis parallel to the axis of the rotary cutter member and having a gap therewith for receiving and discharging a shoe sole, means to maintain proportionate speed ratios of said members relative to each other and to maintain the rotation of said members in opposite directions to move the shoe sole through said gap, shoe sole resistant guide means mounted on the table surface and having a pair of spaced arcuate sole en-

edge engaging surfaces forming a nest therebetween, an intermediate point on one of said sole edge engaging surfaces being disposed in the plane passing through the axes of said members and adjacent said gap and the other sole edge engaging surface lying in the same horizontal plane and spaced from the discharge side of said gap, the plane tangent to the sole edge engaging arcuate surfaces of both of said guide means being disposed at an angle of ninety degrees to the plane passing through the axes of said members.

10. In a shoe sole conditioning machine, the combination of a table surface having an opening, a rotary cutter member capable of producing a lateral thrust in the direction of its rotation and mounted to have a portion of its cutting surface extending through said opening above the surface of said table, a rotary resilient pressure roll member mounted above the table with its axes parallel to the axes of the rotary cutter member and forming a gap therewith for receiving and discharging a shoe sole, means for supporting the rotary resilient pressure roll member for movement relative to the rotary cutter member to increase the gap therebetween, means to maintain proportionate speed ratios of said members relative to each other and to maintain the rotation of said members in opposite directions to move the sole through said gap, shoe sole resistant guide means mounted on the table surface and having an outer arcuate sole edge engaging surface, an intermediate point on said sole edge engaging surfaces being disposed in the plane passing through the axes of said members and adjacent said gap, second shoe sole resistant guide means mounted on said table surface and

10

having an outer arcuate sole engaging surface in the same horizontal plane as the first sole edge engaging surface and spaced from the discharge side of said gap, the plane tangent to the sole edge engaging arcuate surfaces of both of said guide means being disposed at an angle less than ninety degrees to the plane passing through the axes of said members, and adjustable means for regulating the extent of movement of said rotary resilient pressure roll member relative to said rotary cutter member.

11. The structure of claim 10 which also includes means for making said adjustable means ineffective to open the gap between the cutter and the pressure roll members for the insertion and removal of a shoe sole.

12. A guide block for use with the shoe sole conditioning machine consisting of a block member having spaced arcuate sole engaging surfaces lying in a common plane to provide a nest therebetween unoccupied by a sole but bridged by a portion of its arcuate periphery.
